(57) **CLAIM**

The ornamental design for a grounding lug, as shown and described.

DESCRIPTION

FIG. 1 is a perspective view of a grounding lug showing my new design.

FIG. 2 is a right side elevational view thereof.

FIG. 3 is a left side elevational view thereof.

FIG. 4 is a front elevational view thereof.

FIG. 5 is a rear elevational view thereof.

FIG. 6 is a top view thereof; and,

FIG. 7 is a bottom view thereof.

The broken line portion of FIGS. 1 and 6 showing the slot of the lug in broken line is included to show unclaimed subject matter only and forms no part of the claimed design.

1 Claim, 7 Drawing Sheets
